BUILDING CONSTRUCTION.

Application filed March 25, 1927. Serial No. 178,173.

This invention relates to building construction and especially to inclined overhanging structures such, for example, as theatre balconies; and aims to effect an economy of material without loss in strength by converting overturning moments into stresses tending to neutralize the stresses caused by downward forces.

The object of the invention is attained by a cantilever construction in which the overturning moments on a main supporting truss or girder, caused by the overhanging load, are received by trusses so associated with the main girder that these overturning moments are converted into forces which tend to relieve the downward load on the main girder, and to neutralize the compression of the upper cord of the main girder and the tension of the lower cord thereof caused by such load.

In order that the invention may clearly be understood, I will describe in detail a specific embodiment of it in a theatre balcony, which is shown in the accompanying drawings, in which:

Fig. 1 is a plan view of a theatre balcony indicating in dotted lines the parts of the framework of the balcony which lie above the level of the lower cord of the main supporting girder;

Fig. 2 is a plan view of the mezzanine floor located under the rear portion of the balcony, showing in dotted lines the supporting framework of the balcony which lies on the level with the lower cord of the main girder;

Fig. 3 is a transverse section of the balcony taken on its center line; and

Fig. 4 is a diagrammatic isometric perspective view of the supporting framework of the balcony, the outline of the balcony being indicated in dotted lines.

The theatre balcony illustrated is of conventional form having an inclined stepped upper surface or floor for the seats, and a horizontal mezzanine floor under the rear part of the balcony floor. The balcony is supported on posts A, A, B, B located near the ends of the balcony so that the entire space below the balcony is left open and unobstructed.

The balcony has a structural steel framework which is carried by the posts A, A, B, B. The principal object of the invention is to make this framework as light as possible,

while giving it sufficient strength to support the balcony.

The steel framework includes as its principal members, a longitudinal main truss girder 10, tapering balancing trusses 15 extending transversely from the ends of the main truss girder, transverse tapered cantilever trusses 20, a longitudinal upper truss 30, and a longitudinal lower truss 40.

The main truss girder 10 extends lengthwise of the balcony between the posts A, A with its ends resting thereon. This girder is of substantial height and is positioned in a vertical plane, that is to say, its upper cord 11 lies directly over its lower cord 12. It is provided with the usual struts 14 and diagonals 13.

The three cantilever trusses 20 project transversely from the main girder between the posts, and are carried by the main girder. The height of the tapered cantilever trusses at their rear ends is the same as that of the main girder, so that their upper cords 21 and lower cords 22 may be secured directly to the upper cord 11 and the lower cord 12 of the main girder. The upper cord 21 of each cantilever truss is inclined downwardly toward the front end of the balcony, while its lower cord 22 is substantially horizontal, although it may be somewhat downwardly inclined as shown in Fig. 3, or may be truly horizontal as shown in Fig. 4. The cantilever trusses have struts 23 and diagonals 24.

The overhanging weight of the cantilever trusses and the load carried thereby causes an overturning on the main girder, which tends to cause the upper cord 11 of this girder to move forward and the lower cord 12 thereof to move backward. To resist the overturning at the ends of the main girder 10, the ends of the girder are held against forward or rearward bending by triangular stiffening or balancing trusses 15, which project from the end struts 14' of the main girder in a direction approximately perpendicular to the girder. While the stiffening trusses 15 might be extended either forwardly or rearwardly from the main girder, I find it desirable to extend them forwardly and incline them outwardly a little. This brings them in the front corner portions of the balcony, and places their outer ends 16 so that they

may conveniently be held by posts B located at or near the side walls of the theatre, and, at all events, outside the auditorium space. The stiffening trusses 15, thus held at their outer ends, cooperate with the posts A, A in holding the end points, *a*, *a*, *b*, *b*, of the upper and lower cords of the girder 10 against downward movement and against horizontal movement. The overturning moments on the intermediate portion of the main girder are carried at these four fixed supporting points, *a*, *a*, *b*, *b*, being transferred to these points by means of longitudinal trusses next to be described.

15 The forward component of the overturning on the intermediate portion of the upper cord 11 of the main girder between the supporting points *a*, *a*, is received and transferred to the points *a*, *a*, by the longitudinal truss 30, which extends between the supporting points *a*, *a*, and lies behind the girder in the plane of the upper cords 21 of the cantilever trusses 20. The truss 30 has a rear compress cord 31. The upper cord 11 of the main girder serves as the front cord of the truss 30, while rearward extensions of the upper cords 21 of the cantilever trusses provide the struts 33 of the truss 30. The truss 30 is also provided with diagonals 34. The rear edge 20 of the truss 30 may be supported against downward movement in a wall C (see Fig. 3), or in any other convenient manner as by appropriately positioned posts or girders.

The truss 30 is supported at its front corners at the supporting points *a*, *a*, and serves to resist the forward overturning on the upper cord 11 of the main girder, which is also the front cord of the truss 30. As, however, the forward overturning force on the cord 40 11 acts horizontally while the resisting pull of the truss 30 acts at an angle to the horizontal, there are unbalanced components of the forward overturning force, one of which acts vertically upward on the main girder, 45 thus tending to balance the downward load on this girder, and making it possible to make the girder lighter than would otherwise be possible. Furthermore, the compression strain of the upper cord 11 of the main girder, 50 caused by the downward load on this girder, is partially neutralized by the tension strain placed on this same cord 11 by the loading of the truss 30 of which the cord 11 is also a part. This partial neutralizing of the compression strain on the cord 11 makes it possible to make this cord lighter than would otherwise be the case. It may be noted that the upward inclination of the truss 30 is not essential in obtaining this neutralizing of the 55 compression strain in the cord 11.

The rearward overturning on the intermediate part of the lower cord 12 of the main girder between the supporting points *b*, *b* is received and transferred to the points *b*, *b*, by 60 the longitudinal truss 40, which extends be-

tween the supporting points *b*, *b*. The truss 40 lies approximately in the plane of the lower cords 22 of the cantilever trusses 20. Its rear cord 41 may lie directly under the rear cord 31 of the truss 30. The lower cord 70 12 of the main girder serves as the front cord of the truss 40, while rearward extensions of the lower cords 22 of the cantilever trusses provide the struts 43 of the truss 40. This truss is also provided with diagonals 44. 75

The truss 40 is supported at its front corners at the supporting points *b*, *b*, and carries the rearward component of the overturning on the intermediate part of the lower cord 80 12 of the main girder. The compression strain, which the cord 12 receives as the front cord of the truss 40, partially neutralizes the tension strain on this cord 12 caused by the downward load of the main girder of which it is the lower cord. This makes it 85 possible to make the lower cord 12 of the main girder lighter than would otherwise be possible.

From the above description, it will be seen that the overturning moment on the intermediate portion of the main girder 10 are resisted by the trusses 30, 40 in such manner as to convert them into forces which (1) partially counterbalance the downward load on the main girder, (2) partially neutralize the compression strain in the upper cord of the main girder, and (3) partially neutralize the tension strain in the lower cord of the main girder. Any one of these three effects would make possible a reduction in the weight of 90 the main girder; while, when, as in the embodiment of the invention which has been described, all three of these effects are combined, the weight of the main girder may be made approximately 80% of that which 95 would be necessary to carry the load upon it without such counterbalancing. 100

To the main elements of the framework which has been described may be added such light structural steel work as is found most 110 convenient to support the flooring of the balcony and mezzanine flooring under the rear portion of the balcony. As such subsidiary framework may be arranged in various ways with which structural engineers are familiar, 115 a detailed description thereof is considered unnecessary.

It should be noted that the main framework is so arranged that it does not obstruct the space below the balcony, and, in particular, that the struts and diagonals of the trusses 30, 40 are positioned so as to leave space for conveniently located stairs D from the balcony to the mezzanine floor, and stairs E from the mezzanine floor to the main floor. 120

What I claim is:

1. In building construction, the combination of a girder positioned with one of its cords directly above the other, supports for the ends of the girder, tapering balance 130

- trusses extending forward from the ends of the girder and having the rear ends of their upper and lower cords secured to the ends of the upper and lower cords of the girder, 5 means for supporting the front ends of said balance trusses, a forwardly overhanging load carried by the intermediate portion of the girder, and means for applying the overturning moment of such load at the junctures 10 of the girder and balance trusses, such means comprising two longitudinal trusses located behind the girder, one of which extends between the rear ends of the upper cords of the balance trusses and has its front cord coincident with the upper cord of the girder, and the other of which extends between the rear ends of the lower cords of the balance trusses and has its front cord coincident with the lower cord of the main girder. 15
- 20 2. In building construction, the combination of a girder having one of its cords directly above the other, means for holding each end point of each cord of the girder against downward and against horizontal movement to provide four fixed supporting points, a forwardly overhanging load carried by the girder causing overturning moments on the girder between said supporting points, and means for resisting said overturning moments comprising a longitudinal truss 25 extending between the upper supporting points having its front cord coincident with the upper cord of the girder and its rear cord behind the girder, and a second longitudinal truss 30 extending between the lower supporting points having its front cord coincident with the lower cord of the girder and its rear cord behind the girder. 35
3. In building construction, the combination of a girder having one of its cords directly above the other, means for holding each end point of each cord of the girder against downward and against horizontal movement to provide four fixed supporting points, a forwardly overhanging load carried by the girder causing overturning moments on the girder between said supporting points, and means for resisting said overturning moments comprising a longitudinal truss 40 extending between the upper supporting points, having its front cord coincident with the upper cord of the girder and its rear cord to the rear of and above the upper cord of the girder, and a second longitudinal truss 45 extending between the lower supporting points, having its front cord coincident with the lower cord of the girder and its rear cord to the rear of and on a level with the lower cord of the girder. 50
- 50 4. The combination with two spaced supports, of a wedge-shaped structure bridging and overhanging said supports, and having a framework comprising a main longitudinal girder extending between the supports with 55 its ends supported thereon and having its upper and lower cords in a common vertical plane, tapering trusses extending transversely from the ends of the main girder and held at their outer ends, a plurality of tapering cantilever trusses projecting forwardly from the main girder between the supports and having the rear ends of their upper and lower cords secured to the upper and lower cords of the main girder, an upper longitudinal truss 60 extending between the ends of the upper cord of the girder with its front cord coincident with the upper cord of the main girder and lying in the plane of the upper cords of the cantilever trusses, and a lower longitudinal truss extending between the ends of the lower cord of the girder with its front cord coincident with the lower cord of the main girder and lying substantially in the plane of the lower cords of the cantilever trusses. 65
5. A framework for a theatre balcony, comprising two posts, a main girder extending between the posts with its ends supported thereon and having its upper and lower cords in a common vertical plane, tapering balance trusses extending forward from the ends of the main girder and having the rear ends of their upper and lower cords secured to the ends of the upper and lower cords of the main girder, supports for the outer ends of said balance trusses, a plurality of tapering cantilever trusses projecting forwardly from the main girder and having their upper and lower cords secured to the upper and lower cords of the main girder, a longitudinal truss 70 extending between the rear ends of the upper cords of the balance trusses, lying in the plane of the upper cords of the cantilever trusses with its struts formed by rearward extensions of said upper cords, its rear cord connecting the rear end of such struts and its front cord coincident with the upper cord of the main girder, and a longitudinal truss 75 extending between the rear ends of the lower cords of the balance trusses, lying substantially in the plane of the lower cords of the cantilever trusses with its struts formed by rearward extensions of said lower cords, its rear cord connecting the rear end of such struts and its front cord coincident with the lower cord of the main girder. 80
6. In a theatre balcony having an inclined balcony floor and a horizontal mezzanine floor below the rear portion of the balcony floor, a supporting framework comprising two posts, a main longitudinal girder extending between said posts with its ends supported thereon, a plurality of tapering cantilever trusses projecting forwardly from the main girder with their upper cords substantially in the plane of the balcony floor and their lower cords substantially in the plane of the mezzanine floor, a longitudinal truss lying substantially in the plane of the balcony floor with its front cord coincident with the upper cord of the main girder and its struts and 85

diagonals positioned to leave free spaces for stairways from the balcony floor to the mezzanine floor, a longitudinal truss lying substantially in the plane of the mezzanine floor and having its front cord coincident with the lower cord of the main girder and its struts and diagonals positioned to provide free spaces for stairways extending downward

from the mezzanine floor, tapering trusses extending forwardly from the ends of the main girder so that their outer ends are near the front corners of the balcony, and means for supporting the outer ends of said trusses.

In testimony whereof I have hereunto set my hand.

ARTHUR L. BOBBS.
